[57] CLAIM

The ornamental design for a cutting insert, as shown and described.

DESCRIPTION

FIG. 1 is a perspective view of an alternate cutting insert showing a modified embodiment of our new design; FIG. 2 is a top plan view of the cutting insert of FIG. 1, with the bottom view being a mirror image thereof; FIG. 3 is a side elevational view thereof, with the remaining side elevational views being a mirror image thereof; FIG. 4 is a perspective view of an alternate cutting insert showing a modified embodiment of our new design; FIG. 5 is a top plan view of the cutting insert of FIG. 4, with the bottom view being a mirror image thereof; and, FIG. 6 is a side elevational view thereof, with the remaining side elevational views being a mirror image thereof. The broken line showing is for illustrative purposes only and forms no part of the claimed design.
